JOHN F. O'CONNOR, OF CHICAGO, ILLINOIS, ASSIGNOR TO W. H. MINER, INC., OF CHICAGO, ILLINOIS, A CORPORATION OF DELAWARE

SWIVELED COUPLER CONNECTION

Application filed June 4, 1931. Serial No. 542,047.

This invention relates to improvements in swiveled coupler connections.

One object of the invention is to provide a swiveled coupler connection for draft gears of railway cars, wherein the coupler shank is supported for lateral swinging movement by means swiveled directly on the fixed underframe structure of the car, thereby providing a rugged supporting and guiding structure for the coupler shank.

10 A further object of the invention is to provide a supporting guiding means for the shank member of a standard coupler, which provides for lateral swinging movement of the coupler without modification of the shank, lateral swinging movement being obtained by pivotal movement of the supporting and guide means on the fixed underframe structure of the car.

20 Other objects of the invention will more clearly appear from the description and claims hereinafter following.

In the drawings, forming a part of this specification, Figure 1 is a horizontal, longitudinal sectional view through the underframe structure of a railway car, illustrating my improvements in connection therewith. Figure 2 is a vertical, longitudinal sectional view, corresponding substantially to the line 2-2 of Figure 1. Figure 3 is a vertical, transverse sectional view, corresponding substantially to the line 3-3 of Figure 2. Figure 4 is a view similar to Figure 1, illustrating another embodiment of the invention. And Figure 5 is a vertical, longitudinal sectional view, corresponding substantially to the line 5-5 of Figure 4.

Referring first to the embodiment of the invention illustrated in Figures 1, 2, and 3, 40 10-10 indicate channel-shaped center or draft sills of the railway car underframe to the forward ends of which is secured a combined stop and striking casting 11 having side walls 12-12 formed integral therewith, the side walls 12 being provided with aligned 45 coupler key guide slots 13-13. The coupler key guide slots are reinforced along the edges of the openings by internal and external flanges 14-14, the flanges 14 on the inner sides 50 thereof being seated within openings pro-

vided in the vertical webs of the sills 10-10. A combined filler and rear stop casting 15 is fixed to the sills. The shock absorbing mechanism of the railway draft rigging is indicated by 16, the same being of the friction type and having a friction casing provided with an integral rear follower member 17. As will be understood, the usual friction shoes and wedge member cooperate with the friction casing, the wedge member being 60 indicated by 18. Inward movement of the friction shoes with respect to the casing is opposed by the usual spring contained within the casing. A saddle plate 19 secured to the bottom flanges of the draft sills 10-10 65 slidably supports the friction shell of the shock absorbing mechanism 16.

In carrying out my invention as illustrated in Figures 1, 2, and 3, I provide broadly a coupler A, a yoke B, a carrier sleeve C, a butt block D, a front follower E, and front stop members F-F.

The coupler A is preferably of the standard type, having the usual coupler head 20, part of which only is shown, and a coupler shank 21 extending rearwardly from the head. The forward portion of the coupler shank is preferably tapered, as shown in Figure 1, while the rear end thereof is of substantially uniform cross-section throughout the length thereof. The coupler shank is provided with the usual transverse coupler key opening 22 through which the coupler key 23 extends.

85 The yoke B is of the horizontal type having spaced, longitudinally extending side arms and a transverse rear connecting section. The yoke encloses the shock absorbing mechanism 16 and serves to connect the latter to the coupler. The side arms of the yoke are provided with transversely aligned coupler key guide slots 24-24.

90 The carrier sleeve C is pivotally supported from the underframe structure of the car, the stop members F-F being employed for this purpose. As most clearly shown in Figures 2 and 3, the front stop members F-F are in the form of top and bottom plates secured to the top and bottom flanges respectively of the spaced draft sills 10-10. As 95 100

most clearly shown in Figure 3, each plate F is inwardly offset between the sills 10—10 and is provided with a bearing seat 25 adjacent to the forward end thereof, the bearing seat being disposed centrally between the sills 10—10. Each bearing seat 25 is defined by a bearing opening 26 reinforced by top and bottom cylindrical flanges surrounding said opening. The bearing openings 26—26 of the bearing seats 25—25 of the two stop members F—F are in vertical alignment, as clearly shown in Figures 2 and 3. The inner end edges of the plates F—F form the front stops proper of the railway draft rigging and cooperate with the front follower E in the usual manner.

The carrier sleeve C is of substantially rectangular cross-section and has spaced vertical side walls 27—27, a horizontal top wall 28, and a horizontal bottom wall 29. The bottom wall 29, as shown most clearly in Figures 1 and 2, extends forwardly of the side and top walls and is slidably supported at its outer end on the carry iron member 30 of the striking casting 11. The top and bottom walls of the sleeve C are provided with outstanding vertically aligned trunnion members 31—31 which are journaled in the bearing seats 25 of the members F—F. The side walls 27—27 of the carrier sleeve C are flared outwardly so as to accommodate the flaring portion of the coupler shank therebetween. At the inner ends the side walls are slotted, as indicated at 32—32, to accommodate the coupler key 23 for forward movement in draft. The sleeve portion of the member C is embraced between the side arms of the yoke B, as clearly shown in Figures 1 and 3.

The butt block D is provided with a pocket 33 receiving the butt end of the coupler shank. The rear wall of the butt block D is transversely curved exteriorly, as indicated at 34, the curvature of said surface being on an arc concentric to the pivotal axis of the trunnions of the sleeve C. At the forward end the butt block D bears on the inner end of the sleeve C, the top and bottom walls of said butt block being centrally cut away at the forward ends to accommodate the interior bearing flange of the bearing seats 25—25. The side walls of the butt block are slotted at the forward ends, as indicated at 35—35 to accommodate the coupler key.

The front follower E, which is interposed between the butt block D and the wedge member 18 of the friction shock absorbing mechanism 16, is notched at opposite sides, as indicated, to accommodate the side arms of the yoke. At the forward side, the follower E is provided with a curved bearing seat 37 which corresponds in curvature to the curved rear surface 34 of the butt block and cooperates therewith.

In the operation of the improved railway

draft rigging, as illustrated in Figures 1, 2, and 3, upon buffing or inward movement being applied to the coupler A, the butt block D will be forced rearwardly, carrying the follower E therewith and compressing the shock absorbing mechanism 16 between the follower and the rear stop casting 15. During this action, lateral swinging movement of the coupler is permitted by the action of the sleeve C, which is trunnioned in the top and bottom stop plate members F—F. As will be evident, during the rearward movement of the coupler and the butt block D, the coupler key will slide in the guide slots of the yoke, and the latter will remain stationary. As the coupler moves rearwardly, the shank thereof will slide in the sleeve C. During the pivotal movement of the coupler shank about the vertical pivotal axis of the trunnion members of the sleeve C, the curved bearing seat at the forward side of the front follower will permit of the lateral swinging movement of the rear end portion of the butt block without undue friction between these parts. As will be evident, the forwardly projecting section of the bottom wall of the carrier sleeve for the coupler shank supports the coupler shank forwardly of the keyed connection thereof with the yoke, thereby preventing drooping of the coupler head and maintaining the alignment of the parts.

Upon outward movement of the coupler in draft, the yoke will be pulled forwardly therewith through the action of the coupler key, thereby effecting compression of the shock absorbing mechanism 16 against the front follower E which at such time is held stationary by engagement with the stop members F—F. During the draft action, the coupler shank will be pulled outwardly with respect to the sleeve C, the necessary forward movement of the coupler key being accommodated by the slots 32—32 in the side walls of the sleeve. Lateral swinging movement of the coupler shank during draft action is permitted by the swiveling movement of the sleeve C which is free to turn on the trunnion members thereof.

Referring next to the embodiment of the invention illustrated in Figures 4 and 5, the center or draft sills of the railway car underframe are indicated by 110—110, and the striking casting by 111, these parts being substantially the same as the corresponding parts 10 and 11, described in connection with Figures 1, 2, and 3. As will be understood, the railway draft rigging of Figures 4 and 5 is also provided with the usual rear stop casting and saddle plate which supports the shock absorbing mechanism 116. The shock absorbing mechanism is also of the friction type and corresponds to that indicated by 16 in Figures 1 and 2. The striking casting 111 is provided with side walls which have coupler key guide slots 113—113 therein.

In carrying out my invention, I provide broadly a coupler G, a yoke H, a combined carrier sleeve and front follower K, and front stop members M—M. The coupler G corresponds in all respects to the coupler A hereinbefore described and has a transverse coupler key receiving opening 122 which accommodates a coupler key 123. The yoke member H is similar to the yoke B, being of the horizontal type and having longitudinally extending coupler key guide slots 124 at the forward ends of the side arms thereof.

The combined carrier sleeve and front follower member K comprises a tubular section 140 having top and bottom walls 141 and 142 and spaced vertical side walls 143—143. The side walls are shorter than the top and bottom walls, as clearly shown in Figure 4, the top and bottom walls projecting forwardly of the front edge of the side walls a considerable distance. At the rear end, the tubular section of the member K is closed by a follower plate element 144 formed integral with said tubular section. The follower member 144 has a rearwardly projecting central portion 145 which has the end face thereof rounded, as indicated at 146, and bearing on the wedge member 118 of the friction shock absorbing mechanism. The side walls of the tubular section of the sleeve are slotted, as indicated at 147—147, accommodating the coupler key for longitudinal movement. The sleeve also has top and bottom trunnion members 148—148 which are formed integral with the top and bottom walls and cooperate with guide means on the stop members M—M, as hereinafter pointed out. The forward end of the carrier member K is supported on the carry iron member 130 of the striking casting 111, thereby supporting the coupler shank closely adjacent to the head of the coupler and preventing drooping of the head, thus maintaining the parts of the rigging in proper horizontal alignment.

The front stop members M—M are in the form of plates secured to the top and bottom flanges of the draft sills 110—110. The plates M—M are provided with longitudinally extending, vertically aligned guide slots or ways 149—149 which accommodate the trunnion members 148—148 of the carrier sleeve K for longitudinal movement. The slots 149—149 are of such a width as to permit swiveling movement of the trunnions therein but prevent lateral displacement of the latter. At the inner sides, the plates M—M are provided with flanges which surround the slots or openings 149 so as to reinforce these guideways. At the rear ends 60 of the slots 149—149, the reinforcing flanges thereof provide stop shoulders 150—150 which cooperate with the follower section 144 of the combined carrier sleeve and front follower K to limit the forward movement of the same. The sides of the follower section

144 of the member K are cut away or notched so as to accommodate the side arms of the yoke.

In the operation of my improved draft rigging as illustrated in Figures 4 and 5, during buffering or inward movement of the coupler, the combined carrier sleeve and front follower K will be forced inwardly through the inward movement of the coupler shank, thereby compressing the friction shock absorbing mechanism 116. Inward movement of the member K is permitted by the trunnions 148—148 thereof which are slidingly guided in the guideways 149—149 of the members M—M. Lateral swinging movement during the buffering action is permitted by the trunnions 148—148 of the member K, the trunnions swiveling in the guideways 149—149.

During a draft action, the coupler G will be pulled outwardly, carrying the yoke H therewith and compressing the friction shock absorbing mechanism 116 against the front follower 144 which is held against movement by the stop members 150—150 of the plates M—M. During this action, the coupler shank will be pulled outwardly of the sleeve portion of the member K. This movement is permitted by the coupler key 123 moving forwardly in the slots 147—147 of the side walls of the tubular section of said member. During the draft action, swinging movement of the coupler is permitted by rocking of the combined carrier sleeve and front follower member K on its trunnions 148—148, the trunnions having bearing engagement with the curved front end walls of the guideways 149—149.

In addition to serving as a supporting and guide member during swiveling movement of the coupler, the combined carrier sleeve and front follower K also serves to maintain the horizontal alignment of the coupler shank with the other parts of the draft rigging, the bottom wall of the tubular portion of the member K serving as a sliding support for the coupler shank forwardly of the keyed connection thereof with the yoke.

I have herein shown and described what I now consider the preferred manner of carrying out my invention, but the same is merely illustrative and I contemplate all changes and modifications that come within the scope of the claims appended hereto.

I claim:

1. In a draft appliance for railway cars, the combination with the fixed underframe structure of the car; of a yoke member; a coupler provided with the usual shank and having a keyed connection with the yoke member; and a carrier element within which the coupler shank is fitted, said element being laterally swingable with respect to the yoke and having top and bottom pivot members

swiveled in bearing openings provided in the fixed underframe structure of the car.

2. In a draft appliance for railway cars, the combination with supports fixed to the car, said supports having vertically aligned bearing openings; of a yoke member; a coupler provided with a shank member having a keyed connection with the yoke member; and a carrier member having trunnions swiveled in said bearing openings of the supports, said carrier having an opening corresponding in cross-section to the cross-section of the coupler shank and receiving the latter.

3. In a draft appliance for railway cars having shock absorbing means at the end thereof, the combination with a yoke member; of supporting members fixed to the underframe structure of the car, said supporting members having vertically aligned bearing seats; a guide sleeve outwardly of the shock absorbing means, said sleeve having top and bottom pivot members engaged in said seats; and a coupler having a shank portion telescoped within said sleeve and extending therethrough to actuate said shock absorbing means in buff, said coupler shank having a keyed connection with the yoke member for actuating said shock absorbing means.

30 4. In a draft appliance for railway cars, the combination with front stop means secured to the underframe structure of the car, said stop means having vertically aligned bearing seats; of a sleeve having top and bottom trunnions swiveled in said bearing seats; a coupler having a shank telescoped within said sleeve; and a yoke keyed to the coupler shank.

5. In a draft appliance for railway cars, the combination with front stop means fixed to the underframe structure of the car, said stop means comprising top and bottom plate members, said plate members having vertically aligned bearing openings; of a carrier sleeve having top and bottom trunnions swiveled in said bearing openings; a coupler having a shank slidably telescoped within said sleeve; and a yoke keyed to the shank of the coupler.

50 6. In a draft appliance for railway cars, the combination with front stop means fixed to the underframe structure of the car, said stop means presenting top and bottom walls provided with vertically aligned bearing seats; of a carrier sleeve having top and bottom bearing members journaled in said seats; a coupler having a shank slidably telescoped within said sleeve; a yoke member keyed to the coupler shank; shock absorbing means and a front follower within the yoke, said front follower having a curved front surface concentric with the pivotal axis of said carrier sleeve; and a bearing block having a pocket receiving the butt of the coupler shank, said bearing block having a curved

rear surface cooperating with the curved bearing surface of the front follower.

7. In a draft appliance for railway cars, the combination with supporting stop means fixed to the underframe structure of the car, said stop means comprising top and bottom wall members provided with longitudinally extending, vertically aligned guideways; of a coupler having a shank member; a yoke keyed to said shank; and a carrier sleeve within which the shank of the coupler is telescoped, said sleeve having top and bottom trunnion means guided in the guideways of said walls.

8. In a draft appliance for railway cars, the combination with front stop means fixed to the underframe structure of the car, said stop means comprising top and bottom wall members provided with vertically aligned, longitudinally extending guideways; of a coupler having a shank member; a yoke keyed to the shank member of the coupler; a shock absorbing mechanism within the yoke; a carrier sleeve within which the coupler shank is telescoped; top and bottom trunnion members on said sleeve slidably engaged within said guideways; and a front follower member formed integral with the sleeve and engaging the shock absorbing mechanism.

9. In a draft appliance for railway cars, the combination with front stop means fixed to the underframe structure of the car, said stop means comprising top and bottom wall members provided with vertically aligned, longitudinally extending guideways; of a coupler having a shank member; a yoke keyed to the shank member of the coupler; a shock absorbing mechanism within the yoke; and a carrier sleeve within which the coupler is telescoped, said sleeve having pivot members engaged within said guideways, said sleeve being closed at the rear end and having laterally outstanding flanges at said rear end providing a front follower member cooperating with the shock absorbing mechanism and front stop means.

10. In a draft appliance for railway cars, the combination with front stop means fixed to the underframe structure of the car, said stop means comprising top and bottom wall members provided with vertically aligned, longitudinally extending guideways; of a coupler having a shank member; a yoke keyed to the shank member of the coupler; a shock absorbing mechanism within the yoke; a carrier sleeve within which the coupler shank is telescoped, said sleeve having top and bottom pivots engaging within said guideways; and a front follower member closing the rear end of said sleeve and formed integral therewith, said follower member having a curved rear bearing face cooperating with the shock absorbing mechanism.

11. In a draft appliance for railway cars, the combination with the fixed underframe

structure of a car; of a yoke member; a carry iron; a coupler provided with the usual shank and having a keyed connection with the yoke member; and a carrier element with-
5 in which the coupler shank is telescoped, said element being laterally swingable with respect to the yoke and having top and bottom pivot members swiveled in bearing means provided in the fixed underframe structure
10 of the car to permit said swinging movement, said carrier element being slidably supported at its forward end on the carry iron.

12. In a draft appliance for railway cars, the combination with top and bottom sup-
15 porting members fixed to the underframe structure of the car, said supporting member

having vertically aligned bearing seats; of a carry iron element; a guide sleeve having top and bottom pivot members engaged within said bearing seats and guided therein for longitudinal movement, thereby permitting longitudinal movement of the guide sleeve; and a coupler having a shank portion telescoped within said sleeve, said coupler hav-
70 ing a keyed connection with the yoke member of the draft rigging, said coupler being supported forwardly of the keyed connection thereof by said guide sleeve, and said guide sleeve being slidably supported at its forward end on the carry iron of the draft rigging.
